UNITED STATES PATENT OFFICE.

CHARLES LA DOW, OF ALBANY, NEW YORK.

SPRING-TOOTH HARROW.

SPECIFICATION forming part of Letters Patent No. 431,594, dated July 8, 1890.

Application filed June 20, 1889. Serial No. 314,917. (No model.)

To all whom it may concern:

Be it known that I, CHARLES LA DOW, a citizen of the United States, and a resident of the city and county of Albany, in the State of New York, have invented certain new and useful Improvements in Harrows, of which the following is a specification.

The objects of my invention are to secure a simple and strong frame and to mount teeth and clod-crushing devices thereon in such manner that all the parts may be held firmly in position, while capable of being removed or replaced by detachable fastenings involving the use of a minimum number of clamping nuts or bolts. These ends I attain by constructing the frame of a series of diagonal beams, connected by a corresponding series of transverse truss-rods inclosed by spacing-thimbles interposed between the beams, between the ends of which thimbles the teeth are clamped at their point of contact with the beams, while the clod-crushers are mounted upon sleeves encircling their appropriate spacing-thimbles.

The subject-matter claimed is hereinafter specified.

The accompanying drawings represent so much of a harrow embodying all my improvements as is necessary to illustrate the subject-matter claimed. Some of these improvements may be used without the others, and in machines differing in some respects in their details of construction from those herein shown. Unless otherwise designated the parts are of usual well-known construction.

Figure 1 is a plan, and Fig. 2 a side elevation. Fig. 3 is a perspective view, partly in section, from below, showing the mode of clamping the teeth in position. Fig. 4 is a transverse section through the clod-crushing device.

The frame-beams may be composed of wood or metal bars of various shapes; but I prefer to use flat iron beams set up edgewise. The drawings show at the front and center of the machine a boat-shaped octagonal or polygonal structure X, composed of properly-shaped flat bars bolted together, the sides a being parallel and the ends b b' pointed or converging. Projections a' extend outwardly and forwardly from the front of the sides a on each side of the central line of the harrow, sub-

stantially parallel with the other corresponding frame-beams A' A² A³. The converging rear sides of the central frame or structure 55 X are also substantially parallel with the corresponding projection a', above mentioned.

A truss-rod B extends diagonally backward on each side of the frame, passing through the beams a' A' A² A³. Spacing-thimbles C, 60 encircling this truss-rod, are interposed between the beams a' A', and between this latter frame-beam and the frame-beam A². Another, but longer, truss-rod B² extends from the rear part b' of the central frame on each 65 side of the machine, substantially parallel with the front truss-rods above mentioned, and passing through the frame-beams A' A² A³ and through corresponding spacing-thimbles C interposed between these beams. 70

The inner forward frame-beams A' intersect at their rear ends, which are firmly united near the central line or longitudinal axis of the machine. Rear truss-rods B diverge backwardly from this point, substantially parallel 75 with the other corresponding truss-rods and passing through the rear ends of their corresponding frame-beams A' A² A³ and their appropriate thimbles C. The outer frame-beam A³, on each side, is bent inward in front of the 80 central truss-rod, about parallel with the line of draft, and connected to its corresponding front truss-rod at or near its point of intersection with the frame-beam A². 75

The draft attachments may consist of central draft devices, rods, or links, connected with both of the parallel sides a of the central frame X, and by other corresponding devices connected with the forward ends of the frame-beams A'. 85

The harrow is shown as supported entirely upon spring-teeth D, of usual well-known form and construction, curving over and around the thimbles and frame-beams and firmly clamped in position by being grasped edge- 95 wise between the ends of the thimbles C at the points where the truss-rods and frame-beams intersect. The preferred form of clamping the teeth is that shown in Fig. 3, from which it will be seen that the ends c of the 100 thimbles are enlarged and provided with overlapping flanges f, between which the teeth are inserted. The flanges are arranged at a suitable angle to hold the teeth in their proper

position. The front thimbles are enveloped in other thimbles or sleeves Y, capable of turning loosely upon them. These sleeves carry clod breaking or crushing devices, shown as 5 consisting of a central wheel Y', with radial teeth y on each side thereof. The contact of the wheels Y' with the ground causes their rotation, as well as that of the radial teeth, and thus insures the pulverization of the soil 10 by these clod-breaking devices as the machine progresses. Each truss-rod has a head at one end and a clamping-nut upon the other, upon loosening which nut all the teeth clamped thereby may be adjusted, the nut tightened, 15 and the teeth again clamped in their adjusted position.

Under my improved organization—there being only six truss-rods—six nuts only are required to clamp or adjust all the teeth, and 20 as the latter are clamped by the abutting ends of the thimbles, I am enabled to dispense with saddles, clips, and bolt-heads at these points.

So far as I am aware, I am the first to make 25 a spring-tooth harrow of the character illustrated.

I claim as my invention—

1. The combination of frame-beams, truss-rods, spacing-thimbles between the beams, through which thimbles the rods pass, and 30 teeth clamped by their edges between the ends of adjacent thimbles.

2. The combination of frame-beams, truss-rods, thimbles, and spring-teeth clamped by their edges by lips f on the ends of the thimbles, substantially as set forth. 35

3. The combination of two or more frame-beams, the thimbles, a rod B, a clamp nut or device upon one end of the rod, and imperforate spring-teeth gripped by their edges between the ends of the thimbles, whereby a 40 number of teeth may be clamped or loosened by manipulating the clamping device upon the end of a single rod.

4. The combination of frame-beams on each 45 side of the central draft-line extending forwardly and outwardly in parallel or substantially parallel lines, truss-rods passing through the beams and extending outwardly and rearwardly on each side of the machine 50 at substantially right angles to the frame-beams, thimbles on the rods interposed be-

tween the beams, and spring-teeth clamped between the thimbles.

5. The combination of the central structure X, having the sides or portions a' b', the 55 frame-beams A' A', bolted together at their convergent ends, the truss-rods B, and the spring-teeth.

6. The combination, with a gang of imperforate spring-teeth, of securing or clamping 60 devices for simultaneously gripping by their edges or releasing all the teeth of the gang.

7. The combination of the frame-beams, the front truss-rods, the spacing-thimble encircling the rods between the beams, the sleeves 65 turning loosely on the spacing-thimbles, and the radial clod-crushing teeth carried by the sleeves.

8. The combination of the frame-beams, their intersecting front truss-rods, the spacing-thimbles thereon between the beams, the loose sleeves on the thimbles, the radial clod-crushing teeth on the sleeves, and the wheels 70 on the sleeves by which the teeth are rotated.

9. The combination of the diagonal frame-beams, their intersecting truss-rods, spacing-thimbles encircling the rods between the beams, spring-teeth clamped by their edges 75 between the thimbles, sleeves turning loosely on the front spacing-thimbles, and clod-crushing 80 devices mounted on said sleeves.

10. The spring-tooth harrow hereinbefore described, consisting, essentially, of the combination of frame-beams arranged obliquely to the line of draft on opposite sides of the 85 central longitudinal axis, truss-rods intersecting them substantially at right angles, spacing-thimbles enveloping the rods between the beams, spring-teeth clamped between the adjacent ends of the thimbles at their point of 90 intersection with the beams, so that the teeth stand parallel with the line of draft, and clod-crushing devices rotating on the front thimbles, in planes intersecting both the line of draft and of the spring-teeth. 95

In testimony whereof I have hereunto subscribed my name.

CHARLES LA DOW.
